Fraser Kubasta PC(57) **CLAIM**

An ornamental design for a display device with graphical user interface, as shown and described.

DESCRIPTION

FIG. 1 is a front view of a display device with graphical user interface; and,

FIG. 2 is a supplementary view of the claimed portion of FIG. 1 shown isolated and enlarged for clarity of the claimed design.

The dashed line between the three end circles in FIG. 1 form part of the claimed design. The broken lines along the outer perimeter represent a display device and form no part of the claimed design. All other broken line elements, including words with broken lines, illustrate an example interface environment and form no part of the claimed design.
